(57) **CLAIM**

The ornamental design for a two-piece firearms target, as shown and described.

DESCRIPTION

FIG. 1 is a perspective view of a two-piece firearms target showing the new design with the target in an installed position.

FIG. 2 is a front view of a two-piece firearms target showing the new design with the target in an installed position.

FIG. 3 is a bottom view of a two-piece firearms target showing the new design with the target in an installed position.

FIG. 4 is a first side view of a two-piece firearms target showing the new design with the target in an installed position.

FIG. 5 is a rear view of a two-piece firearms target showing the new design with the target in an installed position.

FIG. 6 is a second side view of a two-piece firearms target showing the new design with the target in an installed position.

FIG. 7 is a top view of a two-piece firearms target showing the new design with the target in an installed position; and, FIG. 8 is a plan view of a two-piece firearms target showing the new design with the target in an uninstalled position with the two pieces separated from one another.
